BOBBIN BOARD

Raldo E. Shipman, Sunbury, Pa.

Application February 21, 1946, Serial No. 649,258

9 Claims. (Cl. 242—130)

1

This invention relates to bobbin boards or cone boards such as are used in textile mills for storing and transporting cones or bobbins of thread or yarn.

Such boards are subject to rather severe usage, and it has been difficult to provide a construction which will stand up satisfactorily and endure the rough handling to which they are subject.

An object of the present invention is to provide a bobbin board or cone board of this character which shall be exceptionally strong and durable, and which at the same time shall be light in weight and relatively inexpensive in construction.

Another object is to devise a bobbin or cone board having handles by means of which it can be conveniently lifted and carried, the construction being such that a plurality of boards may be stacked one upon the other with the frame of one board fitting on the handles of the board below.

In order that the invention may be readily understood, reference is had to the accompanying drawings forming part of this specification, in which:

Fig. 1 is a plan view of one of my improved boards embodying the invention;

Fig. 2 is a longitudinal vertical section, substantially on the line 2—2 of Fig. 1, looking in the direction of the arrows, and showing two boards stacked one upon the other;

Fig. 2^a is a fragmentary view on an enlarged scale of a portion of the boards shown in Fig. 2;

Fig. 3 is a transverse section on an enlarged scale, substantially on the line 3—3 of Fig. 1, looking in the direction of the arrows;

Fig. 4 is a fragmentary sectional plan view taken substantially on the line 4—4 of Fig. 3;

Fig. 5 is a view similar to Fig. 3, but showing a slightly modified construction;

Fig. 6 is a fragmentary sectional plan view taken on the line 6—6 of Fig. 5;

Fig. 7 is a side elevation of one form of pin which I may employ, parts being in section;

Fig. 8 is a similar view of another form of pin, parts being in section;

Fig. 9 is a fragmentary plan view showing a slightly modified form of strip;

Fig. 10 is a transverse section on the line 10—10 of Fig. 9, looking in the direction of the arrows;

Fig. 11 is a plan view, similar to Fig. 1, but showing a modified construction; and

Fig. 12 is a fragmentary view on an enlarged scale, showing a portion of Fig. 11.

Referring to the drawings in detail, my improved board comprises a rectangular frame con-

2

structed of a pair of side members 1, and a pair of end members 2. Each of these members is of channel shape in cross-section, with the channels opening downwardly.

Inside of this rectangular frame is a grid structure made up of longitudinal and transverse strips, crossing each other at right-angles, as shown in Fig. 1.

These strips are relatively thin and wide and are arranged vertically edgewise. The longitudinal strips 3, extend continuously throughout the length of the frame and have their ends bent over and secured to the frame members 2, as by means of spot-welding, as indicated at 3^a. The transverse strips are each formed of a series of alined sections 4. Each of these sections has its ends bent at right-angles as indicated at 4^a, such bent ends abutting the sides of the longitudinal strips 3, and the bent ends of the sections on opposite sides of each of the strips 3, being substantially in registry.

The space between the side strips 3, and the sides of the frame is filled in by means of short sections 5, having bent ends 5^a similar to the bent ends 4^a, of the sections of the strips 4, and in registry therewith.

Secured to each corner of the grid structure formed by the intersecting strips 3 and 4 is a bobbin-holding pin 6, as clearly shown in Figs. 3, 4 and 7. Each of these pins comprises a piece of a solid bar or rod, each preferably having a rounded upper end and having its lower end shaped to form a pair of wings 6^a. As clearly shown in Fig. 4 these wings are disposed at right-angles to each other so that they fit within the corner between one of the strip sections 4 and its bent end 4^a.

In assembling my improved grid structure and pins, two sections 4, or a section 4 and filler 5, are disposed in alinement on opposite sides of one of the strips 3, with the bent over ends abutting the sides of such strip and in substantial registry, and one of the pins 6 is placed in the position shown in Fig. 4 with its wing 6^a engaging the section 4 and bent end thereof respectively, and then one of these wings, the two bent ends of the strip sections, and the strip 3 between them, are all united by a single spot-welding operation. In other words the four thicknesses of metal are spot-welded together. In addition the other wing is preferably also spot-welded to the adjacent strip section 4.

The welding together at each corner of the bent ends of the transverse strip sections with the longitudinal strips between them, throughout the grid, results in an exceptionally strong and rigid

structure, and by also welding the angularly disposed wings of the pins into the corners formed by the crossing strips they are securely anchored in position and are capable of withstanding severe strains. Due to the depth or width of the strips disposed vertically edgewise, the area of contact between them and also between the wings of the pins and the strips is relatively large and this results in unusually strong joints.

Fitted over each corner of the frame and secured thereto as by welding, is an upright angle member 7. These may be further reinforced by fillets 8, as shown in Figs. 3 and 4.

Spanning the distance between each pair of angle members 7 at the ends of the frame is a substantially horizontal bail member 9, having its ends bent downwardly and secured to the upper ends of the angle members as by welding, as indicated at 9^a in Fig. 3. The pair of angle members 7 and bail member 9 at each end of the frame constitute handles by means of which the board may be lifted and transported.

By reference to Figs. 1, 2 and 2^a, it will be seen that these handles lie substantially in the same vertical planes as the end members 2 of the frame. By virtue of this arrangement the boards may be stacked one upon the other as shown in Fig. 2, and, when so stacked, the channel member 2 of one frame fits over and is supported by the horizontal bail or handle member 9, of the board below, as clearly shown in Fig. 2^a.

In Fig. 5 I have illustrated a slightly modified construction in which, instead of the bail member 9, I form the handle of a strip of sheet-metal having its lower edge rolled into tubular form, as indicated at 11, to provide a hand hold, while the other edge 10 projects upwardly and is adapted to enter the channel 2 of the board above, the same as the bail member 9. In Fig. 5, the sheet-metal handle 10, 11, is welded at its ends to the upright angle members 7 as indicated at 11^a.

By reference to Figs. 5, 6 and 8, it will be seen that I have also illustrated a somewhat modified construction of pin. Instead of making the pin of a solid rod or bar, I may form it of sheet-metal, rolled into tubular form, as shown at 12, the lower end of the pin being bent to form angularly disposed wings 12^a. These wings of course are welded to the bent ends of the strips at each crossing point, the same as previously described and as illustrated in Fig. 6.

In order to impart greater lateral strength to the strips, I may form them as illustrated in Figs. 9 and 10. In these figures the strip, such as 3', has a central portion 13 curved in cross section. This increases the transverse strength of the strip, while, at the same time the flat flanges at the sides of the curved portion afford suitable contact for welding. Moreover, the bent ends, such as shown at 3^b, are preferably flattened out.

In Figs. 11 and 12, I have shown a modified construction of grid which is preferable in some cases.

Instead of placing the sections of the cross strips 4 in alinement as shown in Fig. 1, and described above, I arrange these sections in staggered relation as shown at 4', in Fig. 11. In such an arrangement only alternate sections are in alinement.

I further find that the bending over of the ends of these sections as shown at 4^a, in Figs. 1 and 4, is not always necessary, since the sections may be anchored to the strips 3 by means of the wings 6^a or 12^a, formed at the bottom of the pins as illustrated in Figs. 7 and 8. That is to say, these

wings form the connecting means between each end of a section 4' and the adjacent strips 3. The parts are assembled in the proper position and then one wing of the pin is welded to the strip 3 and the other wing is welded to the section 4'. This makes a strong and rigid joint.

Although, in this modification the bent ends are eliminated at the points of intersection of the longitudinal and transverse strips, such bent ends are retained where the strips are welded to the frame, as at 3^a. Furthermore, the short sections 5' interposed between the frame 1 and the adjacent strip 3, have one end secured to the strip by means of the wings on the pin as described, and the other end is bent over and welded to the frame as shown at 5^a.

What I claim is:

1. A bobbin board comprising a rectangular frame, a grid structure within said frame made up of longitudinal and transverse strips disposed edgewise in planes perpendicular to the plane of said frame and crossing each other at substantial right angles, and a bobbin-holding pin secured to said strips at each crossing point.
2. A bobbin board comprising a rectangular frame, a grid structure within said frame made up of longitudinal and transverse strips disposed vertically edgewise and crossing each other at substantial right angles, one set of strips extending continuously from one frame member to the opposite one, and each of the other set of strips being formed of alined sections having their ends bent at right angles and abutting the continuously extending strips, and a bobbin-holding pin secured within one of the bent ends of each section.
3. In a bobbin board, the combination with a grid structure comprising strips arranged vertically edgewise and crossing each other at substantial right angles, of a bobbin-holding pin having its end formed to provide a pair of wings disposed at right angles to each other and secured in the corner between the strips at each crossing point.
4. A bobbin board comprising a rectangular frame, a grid structure within said frame made up of longitudinal and transverse strips disposed vertically edgewise and crossing each other at substantial right angles, one set of strips extending continuously from one frame member to the opposite one, and each of the other set of strips being formed of alined sections having their ends bent at right angles and abutting the continuously extending strips, and a bobbin-holding pin located at one of the bent ends of each section, the end of said pin being formed to provide a pair of wings disposed at right angles to each other, one of said wings being in contact with said bent end and spot welded thereto and to the adjacent continuously extending strip.
5. The combination with a grid structure made up of strips arranged vertically edgewise and intersecting at an angle, of a series of pins each having its end shaped to form a pair of wings disposed at a similar angle, one of said pins being mounted at each intersection point of said strips and having its wings fitting into the angle therebetween and welded to at least one strip.
6. A grid structure comprising a series of continuous strips disposed in parallel planes, and a series of parallel crossing strips, each crossing strip consisting of a plurality of alined sections, each section extending between a pair of said continuous strips and having bent ends engaging the sides thereof, the bent ends of the alined sec-

tions on opposite sides of one of said continuous strips being substantially in registry and welded to said continuous strip.

7. In combination, a grid structure comprising a series of continuous strips disposed in parallel planes, and a series of strip sections also disposed in parallel planes at an angle to said continuous strips and interposed between them, with their ends abutting the sides of said continuous strips, and a bobbin-holding pin rigidly mounted in the corner formed by the intersection of each continuous strip and strip section.

8. In combination, a grid structure comprising a series of continuous strips disposed in parallel planes, and a series of parallel strip sections disposed at an angle to said continuous strips and interposed between them, with their ends abutting the sides of said continuous strips, and a bobbin-holding pin having its end shaped to provide a pair of wings disposed at a similar angle, and mounted in each corner formed by the intersection of said strips and sections, one of said wings being welded to the strip and the other to the adjacent section, said wings constituting the sole

10

20

connecting means between said strips and sections.

9. In a bobbin board, the combination with a grid structure comprising strips arranged vertically edgewise and one abutting another at substantial right angles, of a bobbin holding pin secured in the corner between the strips at each abutting point and serving as the connecting means therefor.
